UNITED STATES PATENT OFFICE.

JOHN O. WOODSOME, OF SYRACUSE, NEW YORK, AND JOHN H. SWAN, OF CHICAGO, ILLINOIS.

STEAM CIRCULATING AND REGENERATING SYSTEM.

Application filed June 27, 1921. Serial No. 480,621.

To all whom it may concern:

Be it known that we, JOHN O. Woodsome and JOHN H. SWAN, citizens of the United States of America, and residents of Syracuse, county of Onondaga, State of New York, and Chicago, county of Cook, State of Illinois, respectively, have invented a new and useful Improvement in Steam Circulating and Regenerating Systems, of which the

10 following is a specification.

This invention relates to a means for circulating steam through, for example, a series of heating or drying units, and consists in causing the steam to successively pass 15 through said units by the use of ejectors operated by steam or other fluid at sufficiently high pressure to remove water and air and circulate steam, and to change the used steam and condensate into a dry or 20 saturated steam suitable for continued use throughout the series of units.

The invention also relates to multiple steam operated apparatus or steam controlled devices wherein it is desired, irrespective of work performed, to maintain the steam at different temperatures or pressures 25 in its passage in series through said devices. The particular means employed for accomplishing this purpose consists in the use of a plurality of pressure regulators between the operated units, whereby, as the used steam from one unit passes to the next, it leaves a region of higher pressure and enters one of a lower pressure and therefore whatever 30 condensate remains is partly or largely converted into steam at the desired temperature.

Another purpose of the invention is to combine such arrangement of differential regulators with suitably located ejectors for 35 removing air and condensate from the drying units or operated apparatus and converting part of this condensate into steam by forcing the required circulation.

The invention has a number of applications in the arts, but its objects may be accomplished by the system as illustrated in the accompanying drawings, and designed for the requirements of paper making machines.

40 Figures 1^A and 1^B show in diagram the piping arrangement, controlling devices, valves, and other fittings arranged in a suitable manner for applying the invention to a paper making machine.

45 Fig. 2 is a detail for more clearly showing

a pressure regulator at the inlet end of a supply conduit for the ejectors.

Fig. 3 is a sectional detail taken on line 3-3 of Fig. 1^A and illustrating the supply and return fittings for an individual drying 60 roll at the point of communication with the main supply header.

Fig. 4 is a sectional detail of one of the ejectors which is employed in the system for maintaining the desired circulation and effecting the regeneration of used steam or 65 condensate to steam at the desired temperature.

Fig. 5 is a detail illustrating the construction of one of the auxiliary regulators for 70 controlling the supply valves and differential valves.

Fig. 6 is a sectional detail illustrating the construction of a piston operated differential valve.

75

In the paper making art one of the most difficult and important operations is to properly control the temperature and rate of drying of the paper web as it passes over the driers. The wet end of the machine, or 80 what is sometimes referred to as the condensing section, should deliver considerable heat to the paper, but at a low temperature in order not to sear the paper as it would then trap moisture, resulting in uneven drying 85 and requiring excess heat to remove such moisture. The driers further along in the machine should be successively at higher temperatures except that in some cases there is again a slight drop in temperature in the 90 last section. It is essential for good results that an even and low temperature be maintained on the face of the driers, and for this reason all condensate should be removed promptly. Water in the drying rolls also 95 causes them to be strained by unequal expansion, and the paper does not shrink and dry uniformly at the desired rate. The temperature and rate of drying should be increased gradually from the wet end of the 100 machine toward the dry end.

By the use of the present apparatus the paper may be run through the machine faster than is generally possible, and its quality is improved due to fixed graduation 105 of temperature and the proper proportional delivery of heat, and a better finish is imparted to the paper due to more even distribution of moisture. With respect to colored papers, mottling is absent and colors 110

are not bleached or faded due to too high temperatures. The beater-man may, therefore, follow given formulas and not compensate for peculiarities of operation of any one drying machine.

5 The differential valves which are employed in the present system for maintaining the steam dry by insuring a drop in pressure of the steam as it passes through the 10 rolls are disclosed in the application for Patent of John H. Swan, filed January 15, 1917, Serial No. 142,468.

15 A method now commonly used and probably one of the oldest for handling the condensate in a paper drying machine consists in the use of a common supply header having separate connections for delivering steam to each of the drying rolls. Each of these rolls also has a connection to a common return header, resulting in substantially 20 one steam pressure throughout the machine. A steam trap is connected with the return header. This trap is, therefore, common to all of the driers in handling the condensate. Such a method does not provide 25 for graduated temperatures, but simply the handling of the condensate without waste of steam. Due to all the driers carrying the same steam pressure and for the reason that 30 the driers at the wet end do approximately ninety per cent (90%) more work than the driers at the dry end, the pressure in the driers at the wet end drops somewhat below the pressure in the machine supply 35 header. As the driers at the dry end do little work, the steam pressure in these driers is not lowered, and consequently steam blows through the same into the drain header and tends to build pressure in this 40 header nearly equal to the pressure in the supply header. This causes the driers at the wet end to lose pressure and to become 45 filled with condensate. Some forty per cent (40%) of the driers of the machine are so affected. To overcome this undesirable condition, a system of individual traps for each drier return came into use. It was thought that by putting an individual trap on each 50 drier return steam would be prevented from blowing through the driers into the drain header thereby allowing the condensate to be removed from each drier. In practice, however, it was found necessary to add a vacuum 55 pump to lower the pressure in the return header and to drill a small hole through the traps to permit the desired action of the vacuum pump on the return header to help bring the condensate up the siphon pipe in each drier or to overcome the head in bringing 60 the condensate in the bottom of the drier to the center or journal through which the siphon pipes pass. This individual trap system is much in use, but is still unsatisfactory for not properly emptying the driers 65 of condensate. Accordingly, paper machine

builders have attempted to empty the driers by placing buckets just inside the shell forming the same, but were not successful due to the fact that after the drier obtains a peripheral speed greater than five hundred 70 feet per minute the condensate in the drier is thrown by centrifugal force outwardly, where it forms a film or flat sheet revolving with the cylinder.

Referring to the drawings, Figure 1^A 75 and 1^B, the paper web passes over the customary arrangement of cylinders or driers 1, from the wet end 2 of the machine to the dry end 3. Steam enters the system 80 through a main controlling valve 4 for regulating the pressure of the steam delivered to the machine. This valve is controlled by an auxiliary 5 installed as illustrated in Fig. 1^A. The supply header 6 for the machine is divided into a plurality of sections, 85 for example, 7, 8, 9, by differential pressure regulators 10 and 11. The steam enters the header 6 at the section 7. The pressures in the sections 8 and 9 are respectively controlled by the differential regulators 10 90 and 11. Sections 7 and 8 of the header are connected to a plurality of driers by the conduits 12 and 13, individual to each drier. Corresponding connections to driers from section 9 are indicated by numbers 14 and 95 15. The steam in leaving the header to a drier passes successively through the fittings 16, 17, 18 and the conduit 12, and a hollow trunnion of the drier. One of the bearings 100 for the drier as usual surrounds this trunnion. The siphon pipe 13 for removing condensate from the drier passes through the same hollow trunnion and then downwardly into an ejector 20 by means of which used steam and condensate is forced through the 105 conduit 24 passing centrally through sleeve 16 back into the supply header.

Steam at high pressure, or superheated steam or water for the ejectors is supplied 110 through the header 25, the pressure of this steam being controlled by piston valve 26 which is controlled by the automatic regulator 5. The header 25 has an individual connection 27 with each ejector 20. The construction of the ejectors 20 is shown in 115 Fig. 4. The used steam and condensate from a drier enter the ejector through a screwed connection 28. The live steam for operating the ejector enters at the top passing through the nozzle 30 and then downwardly 120 through the venturi 31 to the header 6. The used steam from a drier is drawn into the venturi 31 through the gap 32, but the ejector is a two-stage arrangement since 125 apertures 33 are provided in the venturi. The condensate is drawn into these apertures and therefore does not interfere with circulation as effected by the ejector as would be the case if water clogged the same at the gap 32. The live or superheated steam 130

or water or whatever fluid is employed for operating the ejectors is of sufficient temperature to insure the regeneration of steam from the condensate removed from the 5 driers.

The differential regulators 10 and 11 control temperatures in the paper machine by insuring successive drops in steam pressure but function similarly to the ejectors in respect to causing condensate to flash back into steam when the steam from one section of the header passes through a differential regulator into a section where a lower pressure is maintained.

15 Fig. 1^B illustrates the connections for the last two driers through which the steam passes. These are located at section 9 of the main supply header. The return for the last driers passes direct to conduit 34 leading to a 20 vacuum pump which serves to draw out air and water, but the pressure in the driers of this section, whether above or below atmosphere, is controlled by differential valve 11. The section 9 of the header is also connected to the vacuum pump through the 25 steam trap 36.

The different sections of the main header 6 may be separated by differential valves as illustrated in Fig. 6.

30 The main header is provided with a drip by-pass 40, 41 around each section for use in carrying air or condensate when steam is first turned into the machine. After the paper is on the machine and complete circulation is established, condensate largely disappears and these by-passes are handling a minimum amount of condensate.

Steam traps 42 as shown in Figs. 1^A and 1^B are in by-passes around the differential 40 valves and between the different sections of the main header. Each trap 42 receives water from the lower end of one of the differential valve bodies, and releases water to the section of lower pressure in the main 45 header when the water attains a certain height in the trap. The communication between the trap and the section of higher pressure is afforded by conduit 40 and with the section of lower pressure by conduit 43.

50 Differential valves.

The differential valves 10 and 11 are constructed as illustrated in Fig. 6. These valves may be piston or diaphragm operated, the opposite sides of the pistons or diaphragms being respectively under the influences of the pressures in the sections of the main header to the right and left of the valve, or as illustrated in the drawings, these 55 different pressures influence the operation of auxiliary regulators 44 and 45 which in turn control the action of the pistons 46 in the differential regulators. The pistons are fast to valve stems 47, which carry the valves 60 48, and are depressible to open the valves 65

against the action of an adjustable spring resistance.

The auxiliary regulators 5, 44 and 45 each have a diaphragm chamber which is divided by diaphragm 49, Fig. 5. This detail which 70 may illustrate the regulator 44 shows a conduit 50 communicating with the diaphragm chamber below diaphragm 49, and another conduit 51 communicating with the chamber above the diaphragm. The conduit 50 as 75 shown in Fig. 1^A communicates with the section 7 of the main header 6, whereas the conduit 51 communicates with the section 8, through the connecting pipe 52, Figures 1^A and 1^B. The diaphragm in regulator 44 is 80 therefore subject to the opposed pressures in sections 7 and 8. The diaphragm is fast to the valve stem 53 for controlling a valve 54. Water, at for example fifteen pounds pressure, is supplied through the pipe 55, 85 Fig. 1^A, and may waste out of the pipes 56, passing through valves 54 of the auxiliary regulators. If one of these valves is moved toward its closed position by an increase in pressure below the diaphragm 46 and a decrease in pressure above the diaphragm beyond a predetermined minimum as determined by an adjustment of the weights 57 on auxiliary regulators, the water cannot waste at the usual rate, and accordingly 90 builds up a pressure in the pipe 58, and as this pipe communicates with the piston cylinder at a point above the piston 46, Fig. 6, the valves 48 are shifted more or less toward open position, and allow the flow of steam 100 from section 7 to section 8 sufficiently to constantly maintain the desired differences in pressure between the sections 7 and 8. The pressure regulator 45 is similarly connected and controls the differential valve 11, 105 the diaphragm in this regulator being subject on its lower surface to the pressure in section 8, due to the communication provided by conduit 52. The upper side of the diaphragm is influenced by the pressure in section 9 through the conduit 59.

The auxiliary regulator 5 controls the operation of piston operated main control valve 60 and the ejector supply valve 26. The operation of these valves is dependent upon the 115 pressure in section 7 of the main supply header 6. Weights on this regulator are adjusted to urge its valve 54 toward closed position and thus allow a water pressure to be built up above the pistons in valves 60 120 and 26, and opening these valves, permitting steam to flow through the system as regulated by some predetermined maximum pressure in section 7. When this predetermined pressure is reached, the valve 54 125 is again opened by the pressure above the diaphragm of the regulator 5, the communication with section 7 being afforded by the conduit 50. Valves 60 and 26 are constructed like the valve shown in Fig. 6, but the 130

4

spring in the main admission steam valve 60 is of different strength than the spring in valve 26 to insure the closing of valve 60 in advance of the closing of valve 26. 5 A minimum pressure in the supply header 25 for the ejectors is provided by the bypass 61 encircling valve 26, and which is provided with a dash-pot reducing valve 62 of usual construction illustrated in Fig. 2. 10 A novel feature of the present invention is the employment of a steam header common to the different drying rolls or steam using apparatus, which header not only delivers steam to the drying rolls, but receives 15 the used steam from the rolls. Certain features employed in the present system are useful in paper drying machines of the old type where a separate return header is used rather than to return the steam to a common 20 header as in the present case, for instance, the ejectors may be employed in many types of paper making machines to advantage in forcing the required circulation through different driers, and the differential regulators 25 would also greatly improve old types of paper making machines by insuring the exact drops in pressures required throughout the series of drying rolls.

In the operation of the steam circulating system as shown in the drawings, a chief 30 characteristic is that the steam is maintained practically dry or possibly superheated irrespective of the work which it performs in delivering heat to the separate driers. Any 35 desired graduation in temperatures between the rolls or driers of the paper machine may be attained according to the number of differential valves employed. Steam is fed to the section 7, which section carries the highest 40 pressure in the arrangement shown in the drawings. In some installations it is desirable to reduce the pressure in the first section, in which case steam is fed to an intermediate section with a drop in pressure 45 in the adjacent sections on each side. Differential valve 10 insures the desired drop in pressure in section 8, and differential valve 11 in section 9.

Circulation of steam through each drier 50 is effected and maintained at the desired uniform rate by the ejectors 20. Dry steam is fed to each drier, and the moist steam is taken away, condensate in the form of solid water being wholly or largely absent. 55 Moisture is re-evaporated by the superheated steam jets in the ejectors so that dry steam with an excess of temperature is fed back into the supply header, the excess temperature tending to dry out any moisture within 60 the steam header.

The differential valves not only regulate temperature differences between sections, but if necessary insure partial regeneration of steam in the sections of the supply header, 65 the steam passing through these valves at

increased velocity and into an area of less pressure, thus permitting the steam to take up moisture. The pressures between the different sections of the machine may be with certain classes of paper in the following ratio: The dry end section at zero pressure, the next or main section at five pounds pressure, other intermediate sections, respectively at eight inches and fifteen inches of vacuum, and at the pump section twenty inches of vacuum. The steam supplied to the ejectors may be at one hundred pounds pressure. With heavy products such as paper board, the dry end section of the machine carries a pressure of from fifteen to twenty pounds higher than the pressure carried on the main section, but with some other classes of paper it is necessary that the dry end section 11 carry a pressure reduced from that of the main section. The differential valves provide a most perfect means for nicely graduating the temperatures between the different driers. The driers in section 7 are piped direct to a vacuum pump, the vacuum pump for this section taking the place of the ejectors.

Although but one specific embodiment of this invention has been herein shown and described, it will be understood that numerous details of the construction shown 95 may be altered or omitted without departing from the spirit of this invention as defined by the following claims.

We claim:

1. In a paper making machine, the combination of a series of drying rolls, of means for supplying steam to said rolls, and differential pressure regulators for regulating the pressures of the steam in the different drying rolls, whereby predetermined pressure relations between the different rolls may be maintained, and a uniform rise or fall in pressure throughout the entire system is made possible.

2. In a paper making machine, a plurality of drying rolls, means for feeding steam to said rolls, and fluid operated ejectors for determining the rate of flow of steam through the different rolls.

3. In a paper making machine, a plurality of drying rolls, means for feeding steam to said rolls, fluid operated ejectors for determining the rate of flow of steam through the different rolls, and pressure regulators for controlling the pressures in the different 120 drying rolls.

4. A paper making machine comprising a plurality of drying rolls, means for supplying steam to the different rolls, and differential regulators for controlling relatively the 125 pressures in the different drying rolls.

Signed at Syracuse this 10th day of June 1921.

JOHN O. WOODSOME.
JOHN H. SWAN.
